(57) **CLAIM**

The ornamental design for a battery charger for earphone, as shown and described.

DESCRIPTION

FIG. 1 is a perspective view of a battery charger for earphone.

FIG. 2 is a front elevation view thereof.

FIG. 3 is a rear elevation view thereof.

FIG. 4 is a top plan view thereof.

FIG. 5 is a bottom plan view thereof.

FIG. 6 is a right side elevation view thereof.

FIG. 7 is a left side elevation view thereof.

FIG. 8 is a front right perspective view showing the battery charger for earphone of FIG. 1 with a lid open.

FIG. 9 is a rear right perspective view showing the battery charger for earphone of FIG. 1 with a lid open.

FIG. 10 is a front elevation view showing the battery charger for earphone of FIG. 1 with a lid open.

FIG. 11 is a rear elevation view showing the battery charger for earphone of FIG. 1 with a lid open.

FIG. 12 is a top plan view showing the battery charger for earphone of FIG. 1 with a lid open.

FIG. 13 is a bottom plan view showing the battery charger for earphone of FIG. 1 with a lid open.

FIG. 14 is a right side elevation view showing the battery charger for earphone of FIG. 1 with a lid open.

FIG. 15 is a left side elevation view showing the battery charger for earphone of FIG. 1 with a lid open; and,

FIG. 16 is another front left perspective view showing the battery charger for earphone of FIG. 1 with a lid open.

The broken lines shown in the drawings illustrate portions of the battery charger for earphone that form no part of the claimed design.
